H. W. COSTON,
RAILWAY COUPLING.
APPLICATION FILED JUNE 5, 1919.

1,427,942.

Patented Sept. 5, 1922.

Harry William Coston

Attorney.

UNITED STATES PATENT OFFICE.

HARRY W. COSTON, OF PORT ELIZABETH, CAPE PROVINCE, SOUTH AFRICA.

RAILWAY COUPLING.

Application filed June 5, 1919. Serial No. 301,924.

To all whom it may concern:

Be it known that HARRY WILLIAM COSTON, subject of the King of Great Britain, residing at 20 Walker Street, Sydenham, 5 Port Elizabeth, Cape Province, South Africa, has invented certain new and useful Improvements in Railway Couplings, of which the following is a specification.

The present invention relates to railway 10 couplings of the central buffer type and comprising an axially movable buffer head, a draw-bar movable axially and independently of the buffer head, and spring resistance means associated with such head and bar whereby two coupling units are retained 15 in close connection. The purpose of the invention is to provide a coupling of this kind with radial movement which permits such close coupling to be effected and maintained 20 on curves.

In the accompanying drawings,

Fig. I is a projected view partly in section of a coupling constructed according to this invention.

Fig. II is a plan drawn to a smaller scale and illustrating two such couplings connected on a curve.

1 is the buffer head formed with a central opening 2. 3, 3, are rearwardly extending 30 bars to which the head 1 is secured by pin joints 4. Said bars 3 pass freely through a coupler head 5 and bear by their rounded extremities 6 against a yoke 7. Tongues 8 extending from the plungers extend through 35 slots 9 in the yoke 7 and are retained against withdrawal by pins 10.

The yoke 7 is formed with a parti-cylindrical thrust bearing 11 seated in a thrust block 12, the yoke being cut away at 32 to 40 allow it to tilt relatively to the draw-bar. The block 12 in turn bears against a compression spring 13 which thrusts against a washer 14 seated on an attachment 15 secured to the drag girder of the vehicle.

45 The coupler head 5 is secured by a pin 16 to the draw bar 17, which extends through the drag girder attachment 15. The coupler head is formed with a semi-cylindrical rear end 18 so that when the latter 50 bears on the yoke 7, it leaves the yoke free to swing in its thrust bearing 12. The openings 19 in the coupler head 5 through which the bars 3 pass are such that said head supports the bars 3 (and with them the buffer head 1) against vertical movement whilst 55 permitting them free lateral movement.

The draw bar 17 passes through and supports the yoke 7 and the thrust block 12 and is of square section at 20 to hold said parts from rotating on it. At the rear end of the 60 draw bar is a washer 21 retained in place against a shoulder 33 by a sleeve 22 and a nut 23 screwed onto the end of the draw bar, and locked by a split key 24. The sleeve 22 passes freely through a plate 25 65 fixed to the truck, which plate supports the rear end of the draw bar and limits its movement. A washer 26 seats on the rear face of the drag girder attachment 15 and between said washers 21 and 26 is inserted 70 the compression spring 27. The draw bar is formed with a forwardly directed shoulder 28 adapted to bear against the washer 14; said shoulder conveniently being provided by a sleeve 29 extending between the 75 washers 21 and 14.

In the coupler head 5 is mounted a coupling pin 30 co-operating with a coupling link 31.

In the operation of coupling two vehicles 80 fitted with the device described, the vehicles are pressed together to force in the head 1 and thereby compress the spring 13. The coupling pins 30 of the two vehicles are then linked together and upon the external 85 pressure on the vehicle being released and their being free for relative movement, the force of the spring 13 will cause the buffer head 1 to move outwardly, and—through the contacting buffer head, its coupling pin and 90 the coupling link—to carry the coupler head 5 out with it until both springs 13 and 27 are at substantially equal tension. The tension thus imparted to the spring 27 tends to keep the vehicles close-coupled as though 95 connected by a screw coupling. Additional buffing pressure during running is taken by the spring 13; whilst additional pull on the draw bar is not only resisted by the spring 27 acting on the drag girder attachment 15, 100 but, owing to the presence of the sleeve 29, causes the washer 14 to follow up the spring 13 and thus maintain the buffing pressure between the buffer heads 1. This close coupling action is given effect to on curves as 105 well as when two vehicles are aligned. Fig. II shows in plan two couplings connected when their vehicles are on a curve. The buffer heads 1 remain face to face, both swinging relatively to their coupling heads 5 and their draw-bars 17. The yokes 7 tilt 110 with them whilst remaining in contact with

the thrust blocks 12, and the over all length of the two couplings is not substantially altered.

I claim:

- 5 1. In a central buffer coupling the combination with a buffer head of a drag girder attachment, a yoke, a spring resisting inward movement of the buffer head and disposed around the drawbar between the yoke 10 and said attachment, a drawbar arranged axially of the head, passing through the attachment and arranged for axial movement relatively to the buffer head and the attachment, a washer adapted to bear on the attachment movable with the drawbar and interposed between said spring and drag girder attachment and a second spring resisting outward movement of the drawbar disposed around the drawbar between the 15 rear end of the drawbar and the drag girder attachment.
2. In a central buffer coupling, the combination with a buffer head, of a coupler head, bars supporting the buffer head and supported by the coupler head, a yoke from 20 25

which said bars project, a draw bar secured to the coupler head and passing through said yoke, a drag girder attachment through which the draw bar extends, a washer adapted to bear on the attachment, a spring between the yoke and said washer, a forwardly directed shoulder on the draw bar adapted to bear against said washer, and a spring bearing on the attachment and connected to the draw bar to resist outward movement 30 35 thereof.

3. In a central buffer coupling, the combination with a buffer head, of bars pivoted at the sides thereof, and extending rearwardly, a yoke to which the rear ends of 40 said bars are pivotally secured, a thrust block on which the yoke bears for lateral swinging movement, a coupler head supporting the buffer head and secured to a draw bar and spring transmission means 45 associated with the buffer head and coupler head.

In testimony whereof I affix my signature.

HARRY W. COSTON.
